Patented January 24, 1905.

UNITED STATES PATENT OFFICE.

CLARENCE M. PERKINS, OF ST. LOUIS, MISSOURI.

DESIGN FOR A BODY FOR COFFEE-POTS, SUGAR-BOWLS, OR SIMILAR ARTICLES.

SPECIFICATION forming part of Design No. 37,299, dated January 24, 1905.

Application filed December 9, 1904. Serial No. 236,235. Term of patent 7 years.

To all whom it may concern:

Be it known that I, CLARENCE M. PERKINS, a citizen of the United States, and a resident of the city of St. Louis and State of Missouri, 5 have invented a new, original, and ornamental Design for a Body for Coffee - Pots, Sugar-Bowls, or Similar Articles, of which the following is a specification.

The accompanying drawing is a perspective 10 view of a body according to my design.

What I claim as new, and desire to secure by Letters Patent, is—

The ornamental design for body for coffee-pots, sugar-bowls or similar articles herein shown.

CLARENCE M. PERKINS.

In presence of—

F. Q. BOYLES,
F. F. REISNER.
